UNITED STATES PATENT OFFICE.

JAMES WILLARD BROWN, OF OSCEOLA, ARKANSAS.

GATE.

SPECIFICATION forming part of Letters Patent No. 727,584, dated May 12, 1903.

Application filed November 1, 1902. Serial No. 129,708. (No model.)

To all whom it may concern:

Be it known that I, JAMES WILLARD BROWN, a citizen of the United States, residing at Osceola, in the county of Mississippi and State 5 of Arkansas, have invented a new and useful Gate, of which the following is a specification.

The invention relates to improvements in gates.

The object of the present invention is to 10 improve the construction of swinging gates and to provide simple, inexpensive, and efficient means for enabling a gate to be opened and closed from a distance to avoid dismounting from a horse or vehicle.

15 Another object of the invention is to enable a latch-bar to be operated automatically and to cause the mechanism for actuating the gate to lock the gate in its closed position in order that the separate latch-bar may be dispensed with when desired.

20 The invention consists in the construction and novel combination and arrangement of parts hereinafter fully described, illustrated in the accompanying drawings, and pointed 25 out in the claims hereto appended.

In the drawings, Figure 1 is perspective view of a gate constructed in accordance with this invention and shown closed. Fig. 2 is a 30 sectional elevation of a portion of the gate, illustrating the position of the lever and the link-bar when the gate is open. Fig. 3 is an enlarged detail view, illustrating the construction of the inner adjacent ends of the lever and the link-bar.

35 Like numerals of reference indicate corresponding parts in all the figures of the drawings.

I designates a swinging gate of any desired construction, hinged to a post 2 and connected 40 with an upright 3 by an oscillating lever 4 and a link-bar 5, which when the gate is closed, as illustrated in Fig. 1 of the accompanying drawings, form a straight brace capable of locking the gate in a closed position.

45 The upright is situated a short distance from the hinge-post 2 and is preferably supported by suitable bracing-bars connecting it with the hinge-post.

The oscillating lever has its outer end 50 bent at an angle to form a journal and arranged in a bearing 7 of the upright 3, and

the inner end of the lever is provided on its lower face with a depending eye 8, situated a short distance from the extreme end of the lever and linked into a perforation 9 of the 55 bar 5, whereby the inner ends of the lever and the bar are caused to overlap. The inner overlapping ends of the lever and the bar are reduced and flattened, and the bar is provided with a shoulder 10, formed by re- 60 cessing its upper face, and by this construction the parts are interlocked when in alignment and are securely held against downward sagging in order to form a brace for locking the gate when closed.

65 The depending eye of the lever and the perforation of the link-bar form a hinge connection, and the bar and the lever provide a toggle connection between the gate and the post or upright 3. The lever is provided at 70 one side with a pin 11, to which is connected a link or rod 12, and the latter has attached to it operating-ropes 13, whereby the hinged ends of the lever and the bar are swung upward to cause the gate to open. The momentum of the gate in opening carries the oscillating lever beyond a perpendicular position, and when the gate is open, as illustrated in Fig. 2 of the accompanying drawings, the parts assume the position shown 75 and are adapted to be swung upward by the operating-ropes, which have an equal pull in opening and closing the gate.

80 The operating-ropes extend through a double pulley secured to an arm 13^a, projecting 85 horizontally from the upright 3, and thence extend to and depend from similar arms 14, attached to and projecting horizontally from uprights 15. The drawings show but one of these uprights 15; but it is to be understood 90 that in practice there will be two of the uprights, situated one at each side of the gate and at a suitable distance therefrom to permit the gate to swing to an open position without contacting with a horse or vehicle when 95 operated by a person on horseback or in a vehicle.

The gate may, if desired, be provided with a pivoted latch-bar 16, arranged to engage an inverted keeper 17 and connected at its inner 100 end by a rod 18 or the like with the upwardly-swinging link-bar 5. As the lever and the

link-bar swing upward the inner end of the latch-bar is simultaneously raised to disengage the latch-bar from the keeper 17.

It will be seen that the means for opening 5 and closing the gate are simple and inexpensive in construction and positive and reliable in operation, that they are capable of being readily applied to any ordinary swinging gate, and that they are adapted to operate 10 the latch automatically and also to serve as a latch for locking the gate and to enable the ordinary latch to be dispensed with.

Changes in the form, proportion, and the minor details of construction may be resorted 15 to without departing from the principle or sacrificing any of the advantages of this invention.

What I claim is—

1. The combination with a swinging gate, 20 of an upright located at one side of the rear end of the same, a bearing associated with the upright; a swinging lever having one end bent at an angle and journaled in the bearing, said lever being provided adjacent to its 25 other end with a depending eye, a pin associated with the lever between the eye and journal, a link-bar having one end hinged to

the gate and provided at its other end with a perforation to receive the eye of the lever, said link-bar and lever having their meeting 30 ends overlapped with the end of the lever seated in a recess formed in the link-bar, a link-rod extending upward from the pin of the lever, and operating-ropes connected with the link-rod.

2. The combination with a swinging gate, of an upright located at one side of the rear end of the same, a link hinged at one end to the gate and provided at its other end with a recess, a swinging lever journaled at one 40 end to the upright and pivotally connected at its other end with the link-bar and overlapping the same, with its overlapped portion seated in the recess formed in the bar, a latch-bar pivoted to the gate, and a connection between the inner end of the latch-bar and the link-bar.

In testimony that I claim the foregoing as my own I have hereto affixed my signature in the presence of two witnesses.

JAMES WILLARD BROWN.
